UNITED STATES PATENT OFFICE.

CHRISTIAN PEDERSEN, OF ST. LOUIS, MISSOURI, ASSIGNOR TO LANDIS MACHINE COMPANY, OF ST. LOUIS, MISSOURI, A CORPORATION OF MISSOURI.

HEATING APPARATUS FOR WAX-THREAD SEWING-MACHINES.

No. 895,496.

Specification of Letters Patent.

Patented Aug. 11, 1908.

Application filed March 14, 1908. Serial No. 421,250.

To all whom it may concern:

Be it known that I, CHRISTIAN PEDERSEN, a citizen of the United States, residing at St. Louis, Missouri, have invented a certain 5 new and useful Improvement in Heating Apparatus for Wax-Thread Sewing-Machines, of which the following is a full, clear, and exact description, such as will enable others skilled in the art to which it appertains to 10 make and use the same, reference being had to the accompanying drawings, forming part of this specification, in which—

Figure 1 is a vertical sectional view of a wax thread sewing machine provided with a 15 heating apparatus constructed in accordance with my invention; Fig. 2 is a sectional view taken on the line 2—2 of Fig. 1; Fig. 3 is a sectional view taken on the line 3—3 of Fig. 1; and Fig. 4 is a detail perspective view 20 of the main gasoline burner.

This invention relates to wax thread sewing machines.

The main object of my invention is to provide a wax thread sewing machine having a 25 gasoline heating apparatus of novel construction which keeps several parts of the machine in a heated condition. I have herein shown my improved heating apparatus applied to a wax thread sewing machine in which the shuttle is arranged above the work-table but it will, of course, be understood that said apparatus could be used on various other types of sewing machines without departing from the spirit of my 30 invention.

Referring to Fig. 1 of the drawings which illustrates the preferred form of my invention, 1 designates the wax-pot of the machine, 2 the shuttle mounted in the head 3 of the 35 machine and 4 a vertically disposed flue which extends upwardly from the wax-pot to the work-table 5. The take-up arm 6 and the rolls 7 and 7^a over which the thread 8 passes are arranged inside of said flue, as shown in Fig. 1.

A gasoline burner A is arranged underneath the wax-pot 1 and the fuel is supplied to said burner by a pipe 9 which leads from a tank 10, a valve 11 being provided for controlling the supply of gasoline to said burner. A pipe 12 which is tapped into a lug 13 on

the burner A leads to the head 3 of the machine, as shown in Figs. 1 and 3, and a pipe 14 which is tapped into a lug 15 on said burner leads to a plate 16 that is arranged adjacent to the take-up arm 6, said plate 6 projecting into the flue 4, as shown in Figs. 1 and 2. Gasolene vapor from the burner A flows through these pipes 12 and 14 and the 55 ends of said pipes are spaced away from the head 3 and plate 16, respectively, so that the vapor which emerges from said pipes can be ignited and thus produce two flames that play on the head 3 and plate 16. The 60 flame from the burner A heats the wax-pot 1 and the flame from the pipe 12 heats the head 3 so that the shuttle mounted in said head will be kept heated. The flame from the pipe 14 plays directly on the plate 16 65 and the heat which radiates from said plate passes into the flue 4 and thus keeps the take-up mechanism in a heated condition and also that portion of the thread which extends from the wax-pot to the work-table. 70

A flange 17 which extends downwardly below the bottom of the wax-pot confines the heat from the flame of the burner A, and the portion 17^a of said flange that is located at the front end of the wax-pot is provided with 75 an opening 18 that permits the heat from the burner A to pass upwardly into the flue 4, as shown in Fig. 1, said portion 17^a also being provided with a hole or opening 19 which enables dirt or wax to be removed from the 80 bottom of the flue 4. While I have herein shown only one opening 18 it will, of course, be understood that the part 17^a could be provided with any desired number of openings. 85

When the valve 11 is manipulated to regulate the flame from the burner A the flames from the pipes 12 and 14 will also be regulated, thus producing a heating apparatus in which a single means; namely, the valve 11, 90 is employed for regulating a plurality of flames. While I prefer to provide the machine with a pipe 14 that projects a flame onto the plate 6 for heating the thread and take-up mechanism, I do not wish it to be 95 understood that my broad idea is limited to such a construction as heat from the burner A enters the flue 4 through the opening 18 and thus heats the members arranged inside 100.

- 2
- of said flue. It will, of course, be obvious that I could tap other pipes into the burner A in case it is desired to heat other parts of the machine.
5. A heating apparatus of this construction comprises few parts and can be manufactured cheaply. It keeps several parts of a machine heated from a single gasoline burner A. It can be applied at any time to any 10 type of wax thread sewing machine, and it also permits several heating flames to be regulated simultaneously by manipulating the valve which controls the flame from the main burner.
15. Having thus described my invention, what I claim as new and desire to secure by Letters Patent is:
1. A sewing machine provided with a wax-pot, a gasoline burner for heating said wax-pot, means for supplying fuel to said burner, and a pipe leading from said burner for conducting vapor to a flame that is separate and distinct from that of the burner and which heats an element of the machine; substantially as described.
  2. A sewing machine provided with a gasoline burner that heats one element of the machine, means for supplying fuel to said burner, a pipe leading from said burner for conducting vapor to a flame that is separate and distinct from that of the burner and which heats a different element of the machine, and means for controlling the supply of fuel to the gasoline burner to regulate 35 both of said flames simultaneously; substantially as described.
  3. A sewing machine provided with a gasoline burner for heating an element of the machine, means for supplying fuel to said burner, and a plurality of pipes tapped into said burner so as to conduct gasoline vapor away therefrom and thus produce flames at the ends of said pipes which heat independent elements of the machine; substantially as described.
  4. A sewing machine provided with a wax-pot and a head in which a shuttle is mounted, a gasoline burner for heating said wax-pot, and means for conducting gasoline vapor 50 away from said burner so as to produce a flame which plays on the head of the machine to heat the shuttle; substantially as described.
  5. A sewing machine provided with a wax-pot, a gasoline burner for heating said wax-pot, means for conducting gasoline vapor away from said burner so as to produce a flame which plays on the head of the machine to heat the shuttle, and means for simultaneously regulating said flame and also the flame of the gasoline burner; substantially as described.
  6. A sewing machine provided with a wax-pot, and a head in which a shuttle is arranged, a gasoline burner arranged underneath the wax-pot, and a pipe tapped into said burner and having its opposite end terminating adjacent the head of the machine; substantially as described.
  7. A sewing machine provided with a wax-pot, a head having a shuttle mounted therein, a flue leading from the wax-pot to a point adjacent said head, a gasoline burner arranged underneath the wax-pot, means for permitting the heat from said burner to enter 75 said flue, and a pipe leading from said burner to said head for producing a flame which plays on the head and keeps the shuttle heated; substantially as described.
  8. A sewing machine provided with a wax-pot, a head having a shuttle mounted therein, a flue leading from the wax-pot to a point adjacent said head, a gasoline burner arranged underneath the wax-pot, means for permitting the heat from said burner to enter 85 said flue, a pipe leading from said burner to said head for producing a flame which plays on the head and keeps the shuttle heated, take-up mechanism arranged in said flue, and a separate pipe leading from said burner to produce a flame which heats said take-up mechanism; substantially as described.
  9. A sewing machine provided with a wax-pot, a shuttle, a take-up mechanism, a gasoline burner for heating the wax-pot, and a plurality of pipes tapped into said burner and leading away therefrom so as to produce 95 flames which keep the shuttle and take-up mechanism in a heated condition; substantially as described.
  10. A sewing machine provided with a wax-pot, a shuttle, a take-up mechanism, a gasoline burner for heating the wax-pot, and pipes leading from said burner so as to produce flames which keep the shuttle and take-up 105 mechanism in a heated condition, and a member for simultaneously regulating the flames from said pipe and the flame from the burner; substantially as described.
  11. A sewing machine provided with a wax-pot, a head having a shuttle mounted therein, a take-up mechanism, a plate arranged adjacent the take-up mechanism, a gasoline burner located underneath the wax-pot, and pipes leading from said burner and having their opposite ends terminating adjacent said head and plate so as to project flames onto said members which keep the shuttle and take-up mechanism in a heated condition; substantially as described.
  12. A sewing machine provided with a wax-pot, a flange which depends below the bottom of said wax-pot, a gasoline burner arranged underneath the wax-pot, a flue leading from the portion of the flange that is located at the front of the wax-pot, said flange being provided with a clean-out opening and 125 openings which permit the heat from said

burner to pass upwardly through said flue, a
head having a shuttle mounted therein, and
a pipe tapped into said gasoline burner and
terminating adjacent said head for projecting
5 a flame onto same so as to heat the shuttle;
substantially as described.

In testimony whereof I hereunto affix my

signature in the presence of two witnesses,
this eleventh day of March 1908.

CHRISTIAN PEDERSEN.
